DRIVE-IN BANK TELLER'S WINDOW

George Payne, Bedford Hills, N.Y., and Nicholas L. Maus, Hamilton, Ohio, assignors to The Mosler Safe Company, Hamilton, Ohio, a corporation of New York

Filed Dec. 12, 1966, Ser. No. 4,985

Term of patent 14 years

(Cl. D13—1)

FIGURE 1 is a front perspective view of a drive-in bank teller's window of the present design.

FIGURE 2 is a side elevational view of the drive-in bank teller's window, the opposite side being a mirror image of this side.

FIGURE 3 is a top plan view of the drive-in bank teller's window.

FIGURE 4 is a bottom plan view of the drive-in bank teller's window.

FIGURE 5 is a rear elevational view of the drive-in bank teller's window.

The portions shown in dotted lines are for illustrative purposes only.

We claim:

The ornamental design for a drive-in bank teller's window, substantially as shown and described.
